UNITED STATES PATENT OFFICE.

NATHAN A. HALLWOOD, OF COLUMBUS, OHIO.

DESIGN FOR A SCALE CASING.

Application filed July 11, 1929. Serial No. 22,005. Term of patent 14 years.

To all whom it may concern:

Be it known that I, NATHAN A. HALLWOOD, a citizen of the United States, residing at Columbus, in the county of Franklin and State of Ohio, have invented a new, original, and ornamental Design for Scale Casings, of which the following is a specification, reference being had to the accompany drawing, forming part thereof.

front of the scale casing, showing my new design;

Figure 2 is a similar view showing the rear thereof, and

I claim:

The ornamental design for a scale casing, as shown.

NATHAN A. HALLWOOD.
